FASTENING COUPLET

Dorothy L. Luzzie, St. Louis, Mo.

Application August 16, 1934, Serial No. 740,059

4 Claims. (Cl. 24—201)

This invention relates generally to fastening devices. More particularly, my invention relates to a certain new and useful improvement in, what I term, fastening-couplets and has for its chief object the provision of a couplet especially, though not exclusively, designed for use in connection with women's wearing apparel for, while efficiently securing parts thereof together, permitting relative movement therebetween for comfortably accommodating movement of the body of the wearer, the couplet comprising co-operable or companion members which are of simple, inexpensive, and durable structure, which may be easily sewed or otherwise fixed to the garment or other parts, and which may be conveniently attached and detached one to and from the other.

And with the above and other objects in view, my invention resides in the novel features of form, construction, arrangement, and combination of parts presently described and pointed out in the claims.

In the accompanying drawing,—

Figure 1 illustrates in fragmental perspective a woman's garment equipped with fastening-couplets embodying my invention;

Figure 2 is an enlarged plan view of the couplet with its members in connected or attached relation;

Figure 3 is a longitudinal sectional view of the couplet-members in attached relation; and

Figure 4 shows the couplet-members associated or attached as in Figure 2 for connecting the contiguous or opposed ends of a strap or straps.

Referring now more in detail and by reference characters to the drawing, which illustrates a practical embodiment of my invention, A and B designate the co-operable or companion members of the couplet, which are preferably constructed from any suitable light-weight sheet metal, and which are preferably of diminutive size for their especially designed use, the couplet-members in actual size being preferably quite considerably smaller than here illustrated.

Member A, which I will designate the main or first member of the couplet, comprises integrally a body-portion 1 preferably, though not essentially, of general disk formation, provided centrally and upon a side face thereof with an upwardly headed stud 2, and joined to body-portion 1 by a reduced neck 3, is an elongated eye 4 for ready attachment of the member A, preferably by sewing, to a particular garment-part, the body-portion 1 being also provided intermediate its perimeter and the stud 2 and diametrically op-

posite the eye 4 with an arcuate or widened closed-end slot 5 preferably concentric with the stud 2.

Member B integrally includes an elongated eye 6 for similar ready attachment of the member B to the garment-part, and projecting laterally from the inner bar of eye 6 is a suitably elongated flat-strip having a width and thickness of reduced dimensions relatively to the length and width of the slot 5, such strip comprising an inner end-portion or shank 7 and a longitudinally extending outer end-portion or tongue 8 joined to the shank 7 by an intermediate portion 9 angularly disposed to the shank 7 and tongue 8, so that the tongue 8 is offset, as it may be said, relatively to the shank 7, the tongue 8 being provided or formed at its free end with an aperture 10 for springwise detachable engagement of the tongue 8 over and with the stud 2. For such purpose, in the present instance, owing to the thinness of the metal of the tongue 8, the same is relatively thickened and re-enforced by a spot-welded or otherwise permanently flatwise fixed washer 11 having an aperture registering with, but slightly reduced diametrically relatively to, the aperture 10 of shank 8, as best seen in Figure 3.

For illustration, the couplet is shown in Figure 1, as has been stated, in connection with a woman's garment C, to the upper margin of the front and back of which a plurality, in the present instance, four of the couplet members A are, at their eyes 4, sewed or otherwise fixed. Co-operable with and forming part of the garment C, are shoulder-straps 12, and sewed or otherwise fixed at their eyes 6 to the free ends of the straps 12, are co-operable companion members B, which at their tongues 8 may be freely endwise projected through the slots 5 of the respective members A and then by suitable pressure exerted upon the free end thereof engaged at their apertures 10 over and with the studs 2, as shown. As so connected or joined, the straps 12 are securely engaged with the garment C, requiring positive pressure of the thumb or finger on the tongue 8 for effecting separation, but yet a certain amount of relative lateral or swingable movement between the straps 12 and garment C is permitted, binding which might retard freedom of movement of the body of the wearer being thereby eliminated and the comfortable wearing of the garment upon the person being correspondingly increased.

The fastening-couplets is also equally capable of other uses, such, for instance, in detachably connecting the contiguous or adjacent ends of straps, as the straps D and E, as shown in Figure 4, and it will also be understood that changes in

the form, construction, arrangement, and combination of the couplet parts may be made and substituted for those herein shown and described without departing from the nature and principle of my invention.

Having thus described my invention, what I claim and desire to secure by Letters Patent is,—

1. A fastening-couplet comprising, in combination, a first member having an upstanding stud and a transverse slot, and a second member having a tongue for projection through said slot and having means for engagement over and receiving the stud for securing said members detachably together, said members when so secured together being swingable the one relatively to the other.

10 2. A fastening-couplet comprising, in combination, a first member having an upstanding stud and a transverse slot, and a second member having a shank and a longitudinally extending offset apertured tongue for projection through said slot for engagement over and receiving the stud in said aperture for securing said members detachably together, said members when so secured together being swingable the one relatively to the other.

15 3. A fastening-couplet comprising, in combination, a first member integrally including a disk-shaped body portion provided with an upstand-

ing stud and having a slot intermediate the stud and the perimeter of the body portion, and a second member integrally comprising a shank and a longitudinal extending offset apertured tongue for projection through said slot for engagement over and receiving the stud in said aperture for securing said members detachably together, said members when so secured together being swingable the one relatively to the other.

4. A fastening-couplet comprising, in combination, a first member integrally including a body portion, an attaching eye and a shank connecting the eye and body portion, the body portion having an upstanding stud and a slot intermediate the stud and a margin of the body portion, and a second member integrally including an attaching eye, a shank laterally extending from the eye and a longitudinally extending tongue joined in offset relation to the shank by an intermediate angularly disposed portion, and having an aperture at its free end, said tongue being disposed for projection through said slot for engagement at its apertured end over and receiving the stud in said aperture for securing said members detachably together in relatively swingable relation.

DOROTHY L. LUZZIE.
